UNITED STATES PATENT OFFICE

ALBERT P. BALL, OF DETROIT, MICHIGAN, ASSIGNOR TO BRIGGS MANUFACTURING COMPANY, OF DETROIT, MICHIGAN, A CORPORATION OF MICHIGAN

MOLDING ASSEMBLY

Application filed January 27, 1930. Serial No. 423,791.

This invention relates generally to finish strip or molding assemblies and refers more particularly to metallic finish strips of the snap-on type designed for use as trimming at the edges of window openings in the doors of vehicle bodies.

One of the essential objects of the invention is to provide an assembly of this type in which finish strips for the top, bottom and side edges of the window opening are formed from a single sheet of metal and are adapted to be snapped on the edges of the window opening so as to constitute a framing therefor.

Another object is to provide an assembly in which the finish strip at the lower edge of the window opening has a depending apron portion or flange that overlaps and conceals the upper edge and outer face of the fabric trim panel upon the inner side of the door.

A further object is to provide an assembly that may be readily and accurately manufactured at a comparatively low cost.

With the above and other objects in view, the invention consists of certain novel features of construction, combinations and arrangements of parts that will be hereinafter more fully described and particularly pointed out in the appended claims.

In the accompanying drawings:

Figure 1 is an elevation of a door having a molding assembly embodying my invention;

Figure 2 is a sectional view taken on the line 2—2 of Figure 1;

Figure 3 is a sectional view taken on the line 3—3 of Figure 1;

Figure 4 is a sectional view taken on the line 4—4 of Figure 1;

Figure 5 is a view similar to Figure 1 but showing a slightly modified molding construction;

Figure 6 is a sectional view taken on the line 6—6 of Figure 5.

Referring now to the drawings, 1 is a vehicle body door of the swinging or hinged type having spaced inner and outer panels 2 and 3 respectively of sheet metal provided with interlocking marginal flanges 4 and 5 respectively and provided adjacent their upper ends with registering window openings 6 and

7, and 8 designates the molding or finish strip for the edges of the opening 6 in the inner panel. As shown, the inner panel 2 is provided at the top, bottom and side edges of the opening 6 with inturned flanges 9, 10, 11 and 12 respectively that preferably comprise inwardly opening channels extending longitudinally of the edges of the opening 6 and serve as anchorage strips for the molding 8. For this purpose the outer walls 9', 10', 11' and 12' of the channels are rounded while the inner walls 9'', 10'', 11'' and 12'' are straight and extend at substantially right angles to the bases of the respective channels. Preferably the rounded portions 9', 10' and 12' project laterally from the inner face of the inner panel 2.

As shown, the molding 8 conforms in shape to the channel flanges 9, 10, 11 and 12 and is preferably snapped thereon. Preferably the molding for the flanges is formed from a single sheet of metal and constitutes a one piece framing for the window opening 6.

As illustrated in Figure 1, the molding 8 is curved at 15, 16, 17 and 18 respectively, however, in Figures 5 and 6 the lower belt portion 20 of the molding projects laterally beyond the upright portions 21 and 22 respectively and is provided with a depending apron or flange 24 that overlaps the upper edge and outer face of a panel 25 of fabric trim material secured upon the inner side of the inner panel 2. As shown, this apron 24 extends downwardly from the inner edge of an open return-bent portion 26 of the curved wall 27 of the channel and is substantially parallel to the inner panel 2. It will also be noted that the inner edge 28 of the straight wall 29 of the channel molding 20 is inturned slightly and engages a correspondingly inturned portion or depression 30 in the depending flange 10'' of the channel 10. Thus from the foregoing it will be readily apparent that the molding may be easily and quickly applied to the door and provides a neat and attractive appearance. Moreover, the one piece construction obviates all joints and separate assembly operations. It will also be noted that the upper edge and outer face of the panel 25 of fabric trim material are also

effectively concealed and a neat assembly provided by the construction and arrangement of depending flange 24 with respect thereto.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

1. In a molding assembly, a panel having an opening therein and provided at certain edges of said opening with inturned flanges, and a one-piece framing for the opening snapped upon the inturned flanges aforesaid and constituting a trim or molding therefor.
2. In a molding assembly, a panel having an opening therein and provided at certain edges of said opening with inturned flanges of channel configuration, and a framing for the opening comprising molding formed from a single sheet of metal and snugly embracing said flanges.
3. In an assembly of the class described, a panel having an opening therein and provided at the edges of said opening with laterally projecting flanges of substantially channel configuration, and a one piece framing for the opening snapped upon the channel flanges and constituting a trim or molding therefor.
4. In an assembly of the class described, a panel having an opening therein and provided at the edges of said opening with open return bent portions having marginal flanges, and a one piece framing for the opening having portions conforming in shape to and embracing the open return bent portions and marginal flanges aforesaid.

In testimony whereof I affix my signature.

ALBERT P. BALL.
